UNITED STATES PATENT OFFICE.

LOUIS M. MUSLINER, OF NEW YORK, N. Y.

DESIGN FOR LEATHER.

Application filed June 28, 1922. Serial No. 2,857. Term of patent 7 years.

To all whom it may concern:

Be it known that I, LOUIS M. MUSLINER, a citizen of the United States, and a resident of the city of New York, borough of Manhattan, in the county and State of New York, have invented a new, original, and ornamental Design for Leather, of which the following is a specification, reference being had to the accompanying drawing, forming part thereof wherein the design is characterized by projecting meshing ridges enclosing therebetween a plurality of cigar-

shaped areas, in the bottom of which are embossed a plurality of substantially hexagonal figures.

Figure 1 is a plan view of a sheet of leather, showing my new design.

Figure 2 is a sectional view through Figure 1, approximately on line 2—2.

I claim:

The ornamental design for leather, as shown and described.

LOUIS M. MUSLINER.
